U.S. PATENT DOCUMENTS

1,454,280 A	5/1923	Henrikson
1,982,538 A	11/1934	Reedy
2,183,271 A	12/1939	Wendel
2,261,056 A	10/1941	Dunn
2,282,073 A	5/1942	McDonald
2,383,235 A	8/1945	Brown

DESCRIPTION

FIG. 1 is a top perspective view of a showerhead according to an exemplary embodiment;

FIG. 2 is a side elevation view of the showerhead of FIG. 1; FIG. 3 is a top plan view of the showerhead of FIG. 1; and, FIG. 4 is a bottom plan view of the showerhead of FIG. 1. The ornamental design which is claimed is shown in solid lines in the drawings. The broken lines in the drawings are for illustrative purposes only and form no part of the claimed design. The claimed design is shown fragmented in the mid-portion of the design to indicate non-specified length.
